United States Patent Office.

WILLIAM M. ARMSTRONG, OF MIDDLETOWN, OHIO.

Design No. 3,974, dated April 19, 1870.

DESIGN FOR A BUGGY-BODY.

The Schedule referred to in these Letters Patent and making part of the same

To whom it may concern:

Be it known that I, WILLIAM M. ARMSTRONG, of Middletown, in Butler county, Ohio, have invented a new and useful Design or Pattern for Buggy-Bodies; and I do hereby declare that the following is a full and exact description thereof, reference being had to the accompanying drawings and to the letters of reference marked thereon.

Figure 1 of the drawings represents a rear elevation of my new design for buggy-bodies.

Figure 2 represents a side elevation of the same.

The object of my invention is to provide a neat and comely shape or configuration for buggy-bodies, which shall present less side surface than heretofore, and be lighter in appearance.

In the drawings the two curves 1 and 2 are of nearly the same conformation, and extend from one side of the body to the other, the curve 1 being underneath the body, and the curve 2 at the rear end thereof.

The side pattern A' is cut away in rear of the curve 1, as indicated by the dotted line 4.

The pattern A, with the two curves 1 and 2, constitutes my new design.

The seat B may be shaped as represented in the drawings, or in any other manner to suit the builder.

A rear view of the body presents two graceful curves, 1 and 2, which are nearly alike in their formation and relations to the body A.

The body will be so hung upon the running-gears that, in turning the vehicle around, the front wheel will strike the body in rear of the curve 1, and consequently a shorter turn may be made with the vehicle than could have been done without cutting away the portion indicated by the dotted line 4.

Having fully described my invention,

What I claim, and desire to secure by Letters Patent as my new design for buggy-bodies, is—

The pattern A, as herein described, and as represented in the accompanying drawings.

In testimony whereof I have hereunto set my hand this 10th day of March, 1870.

WM. M. ARMSTRONG.
